Primary Examiner — Katherine Glennon

(57) **CLAIM**

The ornamental design for a watch case, as shown and described.

DESCRIPTION

The patent or application file contains at least one drawing executed in color. Copies of this patent or patent application publication with color drawing(s) will be provided by the Office upon request and payment of the necessary fee.

1.1 is a front view of a watch case, showing the new design;

1.5 is a perspective view of the watch case;

2.1 is a front view of a watch case;

(Continued)

2.2 is a rear view of the watch case;
 2.3 is a right view of the watch case; and
 2.4 is a left view of the watch case thereof.
